UNITED STATES PATENT OFFICE.

NORMAN P. HARSHBERGER, OF CHICAGO, ILLINOIS, ASSIGNOR TO TEE-LOK SHINGLE COMPANY, OF CHICAGO, ILLINOIS, A CORPORATION OF ILLINOIS.

SHINGLE.

Application filed March 29, 1920. Serial No. 369,801.

To all whom it may concern:

Be it known that I, NORMAN P. HARSHBERGER, a citizen of the United States, residing at Chicago, in the county of Cook and State of Illinois, have invented certain new and useful Improvements in Shingles, of which the following is a specification.

This invention relates to shingles for covering roofs, and has for its object the production of suitable shingles for the purpose, the shingles being so formed that the exposed parts thereof may be locked by the adjacent shingles in such a manner that it is impossible for any portion of the exposed parts to be turned up by the wind or by warping or in any other manner. Another object of the invention is to provide shingles of such a shape that they may be cut from strips of material in such a manner that there is substantially no waste whatever in forming the shingles. Another object of the invention is to provide shingles of such shape, that the appearance of the roof, after having been covered by the shingles, will be pleasing to the eye. A further object is to provide shingles of such shape and laid in such a manner that they will so lap over each other as to form a very effective water proof coat for the roof. Other objects of the invention will appear from a consideration of the accompanying drawings and the following description thereof.

Of the drawing Fig. 1 is a plan view of a single shingle, in its completed shape; Fig. 2 is a diagram indicating the manner in which the shingles are cut from a long strip without any material waste; Fig. 3 indicates the manner in which the shingles are laced together in forming the roof; Fig. 4 is a plan view of a plurality of shingles properly assembled on the roof; and Fig. 5 is an edge view of the shingles of Fig. 4.

It is common to make shingles out of various substances which have been formed into sheets, and which are impregnated with preserving and water proof substances. So far as my invention is concerned the material of which my shingles is composed is immaterial, as well as the substance which impregnates or coats the same; but I prefer for the purpose substances which may be formed into sheets or long strips, and then may be conveniently cut by means of dies or otherwise into individual units, and which

are to be applied to the roof in general in a manner somewhat similar to the ordinary manner of applying such shingles. Shingles made in this manner when applied to the roof, being more or less pliable, the exposed portions of the shingles are some times blown upwardly by the wind, or are otherwise bent out of shape, and the consequence is that the appearance of the roof is objectionable, and the protection of the roof is more or less diminished. The portion of the shingle which is thus deformed, is usually the portion which projects below the overlying upper shingles, and, in order to prevent this deformation, I provide means for locking the lower ends of the shingles to the adjacent shingles.

In general the shingles which I provide are T shaped and comprise a main or top portion 10 with a projecting or shank portion 11, the shank portion being that portion which overlies the adjacent shingles and the top portion 10 being covered by the adjacent shingles. As the shank 11 is thus the exposed portion, and the portion most likely to become deformed, I provide tongues or lugs 12 on the lower edges of the shanks 11, and these lugs are adapted to slip under the shoulders 20 of the adjacent shingles, as indicated in Fig. 4. In order to lock these lugs 12 to the roof by the adjacent shingles I provide slots 13, arranged so that the lugs 12 of each shingle may pass through the slots of the adjacent shingles. For instance, in laying the shingles the units 14 and 15 (Fig. 4) are first laid and the unit 16 then has one of its lugs 12 locked under the shingle 14 and the other lug locked under the shingle 15 in the following manner: The lower end 17 of the shingle 16 is of such length and width that it passes into the space formed between the two shingles 14 and 15; and the lugs 12 may then pass under the shoulders 20 of the underlying shingles 14 and 15; and the shingle 16 then may be pulled upwardly, the lugs 12 passing through the slots 13 of the underlying shingles, so that when the shingle 16 is pulled upwardly to its proper place it will occupy the position indicated in Fig. 4 with reference to the underlying shingles 14 and 15 and its lugs 12 are then locked firmly in place by means of the shanks 11 of the shingles 14 and 15.

Referring to Fig. 4 it will be seen that 110

the exposed portion of each of the shingles forms a square like figure 21, the inclined sides of which are more or less regular, so that the appearance of the roof as a whole, 5 while symmetrical, is not painfully plain, but presents a very pleasing appearance. This appearance is increased by the fact that, as is indicated in Fig. 5, the lower edge of each of the exposed portions in flush with 10 the lower edges of the main portions 10 of the two adjoining shingles, so that there is a double butt portion 22 forming in each case the lower edge of the exposed portion; and this gives to the roof the ordinary 15 double butt arrangement of shingles, and thus improves the appearance by giving a decided line of demarcation along the lower edge of the shingle. Further it will be noticed that in laying the shingles in the manner 20 described, when any portion of the roof covering is completed, the lapping of the shingles over the various edges is such that there is no probability of moisture working through to the roof, as the lapping is very 25 material in each case, and comprises, so far as each inclined edge is concerned, a double lapping thereof.

Attention is called to the fact that, although I have shown and described various details of the particular shape of the shingles, particularly with reference to the shank portions 11 yet, in general, the shingle comprises merely a rectangular top portion 10 with a rectangular shank 11 attached thereto in the form of a T; and the laying of the shingles, except for the locking thereof and the appearance thereof, is substantially the same as if plain rectangular T-shaped shingles were used without 35 the locking means. And it will further be noticed that the cutting out of the individual units from the strips of material, whether the plain or the locking units are used, can be performed without 40 any waste of material, by cutting out the units substantially as indicated in Fig. 2.

With particular reference to the exact form indicated in Fig. 1 it will be seen that the lugs 12 of one shingle are formed by cutting out the recesses 18 of the adjacent shingles, the dimensions of the lugs in the recesses being similar, and the portions 11 as a whole are formed by cutting out the large corners from the adjacent shingles. So 50 that there is no waste of material so far as cutting out of the units as a whole is concerned. The material cut out from the slots 13, however, is not made use of so far as the shingles themselves are concerned. 55 In general the shape of the shingle is such that they may be readily cut from long strips of material, and hence are easily and cheaply manufactured, and at the same time they may be laid so as to form a very pleasing and effective covering for the roof, and 60

one in which the shingles will not become deformed by any ordinary means.

Although my invention may be carried out with shingles of other relative dimensions, yet the relative dimensions which I 70 prefer are as follows: The length of the top portion 10 is twice the distance between the inner edges of the slots, or twice the average width of the shank, measured on a line parallel with the top; and the 75 width of the top is twice the length of the shank or the distance the shank projects away from the top, as is indicated by Fig. 1. The length of each lug 12 is equal to the length of each recess 18; and the length 80 of the outer end of the shank including the two lugs, is twice the distance from the edge of the shank where it joins the top to the adjacent end of the top.

I claim as my invention:

85

1. An article of manufacture comprising a T-shaped shingle having a top and an integral shank, the dimensions of the top being substantially twice the average corresponding or parallel dimensions of the shank, the shank comprising lugs projecting from its outer end.

90

2. An article of manufacture comprising a T-shaped shingle having a top and an integral shank, the dimensions of the top being substantially twice the average corresponding or parallel dimensions of the shank, the shank comprising lugs projecting from its outer end, the said shanks 95 projecting from the tops substantially twice the corresponding or parallel dimensions of the lugs.

100

3. A plurality of shingles, each comprising a top and an integral shank, the shank projecting from the central portion of one edge of the top and a lug projecting from each side of the outer end of said shank, and a slot in the edge of said top adjacent each edge of said shank which connects to the top, each of said lugs adapted 105 to pass into a slot of an adjoining shingle 110 when laid on a roof.

115

4. A plurality of shingles, each comprising a body portion, a projecting portion fixed to the body portion and a lug fixed to the projecting portion, said body portion having a slot in its edge, the said lug being positioned so that when properly laid on a roof it will enter a slot in an adjacent shingle, whereby the projecting portion will 120 be locked down on the roof by the body portion.

125

5. A plurality of shingles, each comprising a top and a shank, the shank projecting from one edge of the top, and a lug projecting from each side of said shank, each of said shingles having transverse slots into which enter the lugs of the adjacent shingles, whereby said lugs are locked down.

130

6. A shingle, comprising a substantially

- flat body portion, a shank in the plane of said body portion and projecting outward from one edge thereof, said shank having locking tongues on opposite sides of the same and extending laterally outward therefrom, and said body portion having locking slots on opposite sides of said shank at the base thereof.
7. A shingle, comprising a substantially flat rectangular body portion, a shank in the plane of said body portion, and projecting outward from one side edge thereof between the end edges of the same, said shank having locking tongues on opposite sides of the same and extending laterally outward therefrom, and said body portion having locking slots on opposite sides of said shank at the base thereof and opening through the adjacent edge of said body portion.
8. A roof, comprising a plurality of shingles, said shingles having locking tongues and slots for interlocking the shingles together, the tongues becoming engaged with the slots on moving the shingles with the tongues relatively to the shingles with the slots in directions to cause the tongues to enter the slots.
9. A plurality of shingles, arranged with two shingles end to end and in the same plane, a third shingle laid on said two shingles, said third shingle extending over the joint between said two shingles and overlapping the latter on opposite sides of said joint, said shingles having locking tongues and slots on opposite sides of said joint, the tongues being on said third shingle so that the latter may be interlocked with both of said two shingles by moving said third shingle relatively to said two shingles in a direction to cause said tongues to enter said slots.
10. A plurality of shingles, each comprising a body portion and a shank, two shingles being arranged end to end and in the same plane, a third shingle laid on said two shingles, said third shingle extending over the joint between said two shingles and overlapping the latter on opposite sides of said joint, said third shingle having tongues on its shank on opposite sides thereof, and said two shingles having slots at the bases of their shanks to receive said tongues upon moving the third shingle relatively to said two shingles in a direction to cause said tongues to enter said slots for interlocking said shingles together.
11. A roof comprising a plurality of pliable shingles, said shingles having slots extending in a direction substantially up and down the roof and a part of the lower portion of each shingle extending through a slot in the adjacent lower shingle, whereby the lower edges of the shingles are locked down by the adjacent lower shingles.
- In testimony whereof, I hereunto set my hand.

NORMAN P. HARSHBERGER.
